(57) **CLAIM**

The ornamental design for an effects pedal, as shown and described.

DESCRIPTION

FIG. 1 is a perspective view of an effects pedal showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken line portions of the effects pedal in FIGS. 1-7 represent unclaimed portions of the claimed design and form no part thereof.

1 Claim, 5 Drawing Sheets**FIG. 1**

FIG. 2

FIG. 3

FIG. 4

FIG. 5

FIG. 6

FIG. 7
